UNITED STATES PATENT OFFICE.

EDWARD H. McCLOUD, OF COLUMBUS, OHIO, ASSIGNOR TO THE KINNEAR MANUFACTURING COMPANY, OF COLUMBUS, OHIO, A CORPORATION OF OHIO.

BRAKE FOR FIRE-SHUTTERS.

1,339,380.

Specification of Letters Patent.

Patented May 4, 1920.

Original application filed July 23, 1915, Serial No. 41,532. Patented August 6, 1918, No. 1,275,168. Divided and this application filed June 29, 1918. Serial No. 242,609.

To all whom it may concern:

Be it known that I, EDWARD H. McCLOUD, a citizen of the United States, residing at Columbus, in the county of Franklin and 5 State of Ohio, have invented a certain new and useful Improvement in Brakes for Fire-Shutters, of which the following is a specification.

This invention relates more particularly 10 to centrifugal brakes especially designed for use in connection with automatically closing shutters and the invention has for its principal object to provide an improved construction of such a brake adapted to operate 15 when the curtain is automatically released for closing as in the event of nearby fire.

The invention is embodied in the example shown in the accompanying drawing and set forth in the following specification.

20 In said drawing—

Figure 1 is an end view in elevation with parts broken out showing the brake set to permit ordinary operation of the shutter.

Fig. 2 is a front view.

25 Fig. 3 is an end view in elevation illustrating the brake released for operation.

Fig. 4 is a sectional view.

Fig. 5 is a detail of the brake members.

In the views 6 designates one end of the 30 curtain roller and 7 a bracket for supporting the shaft 8 of said end of the curtain roller. Secured to the end of the shaft 8 where it projects beyond the bracket and to rotate with the shaft is a ratchet wheel 9 having a hub sleeve 10. Loose on said sleeve 35 is a spur gear wheel 11 carrying a pawl 12 pivoted so as to be capable of engaging a tooth of the ratchet. Said pawl has an extended heel 13.

40 Journaled on a suitable bearing 14 extending from the bracket below the spur gear 11 is a pinion 15 having fixed therewith a cross plate or frame to the opposite ends of which are loosely pivoted on pins 16 two brake shoes 17. The shoes 17 have inward projections 17^a at their free ends. Also pivoted on said pins 16 are arms or levers 18 having cams 18^a near their pivots and weighted portions 18^b at their free ends. The cams 18^a 45 are located to press, when turned outward, upon the projections 17^a at the free ends of the shoes. Springs 19 connect the arms 18 with the pins 16, said springs tending normally to hold the cam 18^a out of engagement 50 with the projections 17^a.

Mounted in the bracket 7 is a weighted lever 20 having connected with its inner end a short arm or dog 21 arranged so that when the weight lever 20 is elevated to horizontal position it extends into the path of the heel 60 13 and holds the pawl 12 disengaged from the ratchet 9. The lever 20 is held elevated by means of a wire 22 containing a portion 65 23, fusible by a dangerous rise of temperature, said wire being secured to a suitable fixed point above.

When the parts are arranged, as shown in Fig. 1, the shaft of the roller is free to turn without operating the brake at all. When the weight lever 20 is released, as by a near- 70 by fire, the pawl is thrown into engagement with the ratchet 9 and the gear wheel 11 caused to rotate with the shaft of the roller. Rotation of the gear wheel 11, of course, causes rotation of the pinion 15, and the im- 75 pulsion outward by centrifugal force of the brake shoes and the arms 18 with the cam 18^a. The pressure of the cams 18^a on the brake shoes, because on the extremities of the shoes insures a tight bearing of the shoes 80 against the brake rim 24. The brake rim 24 is conveniently formed in an extension of a suitable hood 25 for the brake mechanism.

In the normal position of the parts, which 85 is that shown in Fig. 1, the shutter or curtain attached to the roller can be rolled up and unrolled as desired without operating the brake at all, because the shaft 8 of the shutter and the ratchet wheel 9 attached thereto run idly in the spur gear 11. When, 90 however, the pawl 12 is released as by the melting of the fusible portion or member 23 and the lever arm 20 drops the pawl 12 swings into engagement with the ratchet wheel 9 and thus operatively unites the shaft 95 with said spur gear wheel 11 and causes it to turn and through it the pinion 15. The rapid rotation of the pinion 15 throws out the brake shoes 17 as well as the arms 18, 100 and the cams 18^a thereof acting on the free ends of the shoes, as illustrated in Fig. 2, engender a firm and extensive pressure of the shoes 17 on the brake rim 24 tending to prevent a too rapid unwinding of the curtain. It will be understood, of course, that 105 where the curtain is one that is counterbalanced for raising and lowering in normal circumstances that thermally actuated means like that at 22—23 will be provided for liberating the counterbalancing means in case 110 110

of fire and that such means can be arranged in position to operate simultaneously or nearly simultaneously with the means for releasing the brake. Indeed the same means, 5 22-23, can be used to hold the counterbalancing spring latched from action.

The number and forms of the parts can be changed without departing from the gist of the invention as claimed.

10 The application for this patent of the United States is a division of an application for patent filed by me on July 23, 1915, S. No. 41,582, patented August 6, 1918, No. 1,275,168.

15 What I claim is—

1. A brake mechanism including, in combination, a brake rim, two opposingly arranged shoes to engage said rim, each of said shoes being pivoted at one end on a

20 pivot within said rim, a centrifugally actu-

ated arm carrying a cam pivoted on the pivot of each of said shoes, the cam on the pivot of one shoe acting on the free end of the other shoe to aid centrifugal action thereof on the brake rim.

25

2. A brake mechanism including, in combination, a brake rim, two opposingly arranged shoes to engage said rim, each of said shoes being pivoted at one end on a pivot within said rim, a centrifugally actuated arm carrying a cam pivoted on the pivot of each of said shoes, the cam on the pivot of one shoe acting on the free end of the other shoe to aid centrifugal action thereof on the brake rim, and a spring connecting the pivot 30 of each shoe with the arm carrying the cam actuating it, said spring tending to withdraw said cam from operation when centrifugal action ceases.

30

EDWARD H. McCLOUD.
